FLAT BEAM CATHODE-RAY TUBE
AND CIRCUIT

Leonard Francis Broadway, Ickenham, England,
assignor to Electric & Musical Industries Limited,
Hayes, England, a company of Great Britain

Application March 6, 1945, Serial No. 581,281
In Great Britain March 9, 1944

7 Claims. (Cl. 250—158)

1

This invention relates to cathode ray tubes and circuit arrangements embodying such tubes.

For some purposes cathode ray tubes are required in which the sensitivity of deflection of the beam across the screen of the tube in one direction is required to be much greater than the sensitivity of deflection in another direction perpendicular to the first. For example, in cathode ray tubes employed in radar equipment a high sensitivity of deflection is required in the signal direction and also in cathode ray tubes employed for television purposes the sensitivity of deflection is required to be much greater in the direction of the line scan than in the direction of the frame scan.

Usually the cathode ray beam is scanned across the screen of the tube either by electrostatic deflecting means or by electromagnetic deflecting means, each deflecting means comprising either a pair of plates or a pair of coils which may be associated with magnetic pole pieces provided within the envelope of the tube. It is known that in order to obtain optimum sensitivity of deflection the deflecting plates or the pole pieces of the coils should be placed as close as possible to the electron beam. Since the beam, which is usually of circular form in cross-section, is brought to a focus at the screen and since it is necessary to dispose the deflecting means at some distance from the screen in order that the focussed beam can scan an area of a desired size, the deflecting means must be disposed at a position where the diameter of the beam is fairly large which results in the sensitivity of deflection being relatively small. If it is desired to reduce the diameter of the beam at the position where the deflecting means are disposed, then it is necessary to step down the beam diameter which is an undesirable expedient owing to the consequent reduction in the beam current.

It is the object therefore of the present invention to provide an improved cathode ray tube and circuit arrangement embodying such tube in which the sensitivity of deflection can be increased in one direction without necessitating a decrease in the available beam current.

According to one feature of the invention there is provided a circuit arrangement embodying a cathode ray tube in which the electron beam of the tube is of elongated form in cross-section, said tube having means for causing said elongated beam to converge to form a small spot on the screen of the tube and in which deflecting means are provided for deflecting said spot relatively to said screen in one direction and de-

2

flecting means are provided for deflecting said spot relatively to said screen in a co-ordinate direction, deflection in one direction occurring at a more rapid rate than the deflection in the other direction, wherein the deflecting means for deflecting the spot at said more rapid rate are disposed at a position where the beam is of elongated form and embrace the longer sides of the beam cross-section thus permitting said deflecting means to be placed closer together than would otherwise be possible, whereby the sensitivity of deflection at said more rapid rate is increased.

According to another feature of the invention there is provided a cathode ray tube having means for generating an electron beam of elongated form in cross-section and having means for causing said electron beam to converge to form a small spot on the screen of the tube and in which deflecting means are provided for deflecting said spot relatively to said screen in one direction and deflecting means are provided for deflecting said spot relatively to said screen in a co-ordinate direction, one of said deflecting means being capable of deflecting the spot at a more rapid rate compared with the rate of deflection produced by said other deflecting means, wherein the deflecting means capable of deflecting the spot at said more rapid rate are disposed at a position where the beam is of elongated form and embrace the longer sides of the beam cross-section thus permitting said deflecting means to be placed closer together than would otherwise be possible, whereby the sensitivity of deflection at said more rapid rate is increased.

Usually, the deflecting means are disposed at separated points along the path of said beam and the deflecting means which deflect the beam at the more rapid rate are disposed in a position where the beam is more elongated compared with the elongation of said beam at the point where the other deflecting means are disposed.

With a cathode ray tube employed in accordance with the invention it is possible to arrange that the beam is of a substantially rectangular form in cross-section, the depth of the cross-section being, for example, of the order of 0.005", the width of the beam being of any suitable size in order to obtain a desired beam current. Where the cathode ray tube employs electrostatic deflecting plates the distance apart from said plates at the point where they approach closest to the beam may be only slightly larger than the depth of the beam thus providing a substantial improvement in the sensitivity of deflection.

Where electromagnetic deflecting means are employed the pole pieces of the deflecting coils need only be spaced apart by a distance slightly larger than the depth of the beam although in this case it will be appreciated that the direction in which increased sensitivity of deflection occurs will be at right angles to that obtained with electrostatic deflection.

In order that the said invention may be clearly understood and readily carried into effect, it will now be more fully described with reference to the accompanying drawing which illustrates one embodiment of the invention as applied to a cathode ray tube employing electrostatic deflecting means.

As shown in the drawing, the reference numeral 1 indicates the envelope of a cathode ray tube, having a screen S. The reference numeral 2 indicates a cathode of elongated form mounted within a cathode shield 3 of rectangular form, the shield 3 having a rectangular slot 4, as shown, for defining the size of the beam emitted from the cathode 2. The shield 3 in, for example, a television reproducing tube may serve as a modulating electrode to which modulated potentials can be applied for varying the intensity of the beam. The beam emanating through the slot 4 is thus of elongated rectangular form and the depth of the slot may be say 0.005" whilst its width will be of a suitable size to permit the passage of a beam of a desired current. Adjacent to the shield 3 is a tubular electrode 5 of rectangular form in cross-section, the end of the electrode 5 adjacent the shield 3 being closed by a plate provided with a rectangular slot 6 therein. The electrode 5 may be maintained at a positive potential when operating the tube and its slot 6, in conjunction with the slot 4 and the potential applied in operation to the shield 3, which will be negative with respect to the electrode 5, serves to produce an electrostatic lens which maintains the beam emanating through the slot 4 sensibly parallel or slightly convergent, with respect to the plane containing the major axis of the slot 4; thus the operation of the electrostatic lens should be such that the electron beam does not increase in depth beyond the depth of the slot 4. It may in some cases be desirable to insert a further electrode or electrodes suitably slotted and maintained at suitable potentials between the electrodes 3 and 5 or the surface of the cathode may be suitably curved in its shorter dimension in order to ensure this result. The electron beam indicated by the dotted lines 7 passing through the electrode 5 is then acted upon by a further electrostatic lens in order to cause the beam to converge so as to form a small spot of a desired size on the screen S. This converging action may be accomplished by employing an electrostatic lens of one of the types described in the specification of British patent application No. 4628/42. Such a lens may comprise a further tubular electrode 8 of rectangular form in cross-section which co-operates with the end of the electrode 5 remote from the cathode, the adjacent ends of the electrodes 5 and 8 being suitably shaped and provided with slots in the manner described in the aforesaid specification so as to afford a convergent beam, the action of the lens formed by the electrodes 5 and 8 being such that the depth of the beam is substantially unchanged whilst its width converges to form a spot of the desired size. In operation the electrode 8 will usually be maintained at a higher potential than the electrode 5 and the electrode 8 may be pro-

vided with a slot 9 in order to define the size of the beam emanating from the electrode 8.

Deflecting means are provided for deflecting the beam relatively to the screen of the tube in one direction and deflecting means are provided for deflecting said beam relatively to said screen in a co-ordinate direction. As shown in the drawing, the electron beam is arranged to be deflected in a direction perpendicular to the plane containing the major axis of the beam cross-section by a pair of plates 10 to which suitable potentials are applied for setting up an electrostatic deflecting field. The pair of plates 10, it will be observed, embrace the longer sides of the beam cross-section and are disposed in a position where the beam is still of elongated form. The deflecting means 11 for deflecting the beam at right-angles to the deflection imparted by the plates 10, are spaced from the plates 10 along the path of the beam and are closer to the screen S of the tube than said plates 10 so that the beam at the point where the other deflecting means 11 are disposed will be less elongated compared with the elongation of the beam at the point where the plates 10 are disposed. In one of the directions of deflection the beam is required to be deflected at a more rapid rate compared with the rate of deflection in the other direction. In the case of a cathode ray tube employed in television apparatus deflection of the beam at the line-scanning frequency is far more rapid than the deflection beam at the frame-scanning frequency. With the tube shown in the drawing the plates 10 will serve to deflect the beam at the more rapid rate whilst the other deflecting means 11, (not shown), will serve to deflect the beam at the slower rate. By arranging the plates 10 in the position shown the sensitivity of deflection at the more rapid rate is increased since the distance apart of the edges of the plates 10 where they are closest to the beam need only be slightly larger than the depth of the beam, i. e., slightly larger than 0.005". In this manner the sensitivity of deflection can thus be made very high whilst at the same time the plates 10 can be disposed at a position to permit an area of a desired size to be scanned. The deflection of the beam in the other direction may be accomplished by the further pair of deflecting plates 11 or by electromagnetic deflecting means. If desired, of course, the plates 10 may be replaced by the pole pieces of electromagnetic deflecting means the pole pieces extending within the envelope 1 and being disposed close to the beam. Where the plates 10 are replaced by pole pieces it will of course be appreciated that the deflection will be in a direction mutually perpendicular to the direction of deflection produced by the plates 10.

It is possible that with the construction described employing a beam of elongated cross-section, a higher modulation slope and a less curved modulation characteristic may be obtained compared with a tube employing a circular cathode. Furthermore, less de-focusing may occur with the modulation potentials and with the potentials applied to the deflecting plates.

I claim:

1. A circuit arrangement embodying a cathode ray tube having means for producing a thin flat electron beam rectangular in cross-section, means for causing said flat beam to converge in width to form a small spot on the screen of the tube deflecting means for deflecting said spot relatively to said screen in one direction and deflecting means for deflecting said spot rela-

tively to said screen in a co-ordinate direction, deflection in said one direction occurring at a more rapid rate than the deflection in the other direction, wherein the deflecting means for deflecting the spot at said more rapid rate are disposed at a position where the beam is rectangular in cross-section to embrace the longer sides of the beam cross-section and placed closed together than would otherwise be possible, whereby the sensitivity of deflection at said more rapid rate is increased.

2. A circuit arrangement according to claim 1, wherein said deflecting means are disposed at separated points along the path of said beam and the deflecting means which deflect the beam at the more rapid rate are disposed in a position where the flat beam is wider than at the point where the other deflecting means are disposed.

3. Television apparatus incorporating a circuit arrangement according to claim 1, in which said deflecting means serve respectively to deflect the beam of the tube at the line-scanning frequency and at the frame-scanning frequency, said deflecting means which embrace the longer sides of the beam cross-section serving to deflect the beam at the line-scanning frequency.

4. A cathode ray tube having means for generating an electron beam rectangular in cross-section and having means for causing said electron beam to converge to form a small spot on the screen of the tube deflecting means for deflecting said spot relatively to said screen in one direction and deflecting means for deflecting said spot relatively to said screen in a co-ordinate direction, one of said deflecting means being disposed at a position where the beam is rectangular in cross-section to embrace the longer sides of the beam cross-section, said deflecting means comprising parallel members spaced a distance only slightly greater than the depth of the cross-section of said beam between said members, whereby the sensitivity of deflection at said more rapid rate is increased.

5. A cathode ray tube according to claim 4, wherein said deflecting means are disposed at separated points along the path of said beam, one of the deflecting means being disposed at a point where the width of the beam is greater than at the succeeding point along the path of the beam where the other deflecting means are disposed. 50

6. A cathode ray tube comprising an evacuated envelope enclosing means for producing a thin flat beam of electrons, a fluorescent screen in the path of said beam, beam focusing means effective only to the width of said beam to focus said beam to a spot on said screen, deflecting means for producing a deflecting field perpendicular to the sides of said flat beam at a region near the said focusing means where said beam is wide, a deflecting means for producing a deflecting field parallel to the sides of said beam at a region more remote from said focusing means and where the width of said beam is less than at the first deflecting field.
- 10 7. A cathode ray tube having a thermionic cathode, a beam forming electrode for forming the electron discharge from said cathode into a thin flat beam rectangular in cross-section, a tubular accelerating electrode for said beam, a focusing electrode adjacent the beam exit end of said accelerating electrode for forming with said accelerating electrode an electrostatic lens effective to converge said beam only in the direction of its width to focus said beam, a pair of 15 deflecting plates positioned near said focusing electrode and disposed on opposite sides of the normal path of said beam to be parallel to the sides of said flat beam and spaced a distance only slightly greater than the depth of the cross-section of the beam between said plates to deflect said beam in a direction perpendicular to the sides of said beam, and a second pair of 20 deflecting plates more remote from said focusing electrode and positioned to deflect said beam in 25 a direction parallel to the sides of said flat beam.
